(57) **CLAIM**

The ornamental design for an atomizer, as shown and described.

DESCRIPTION

FIG. 1 is a perspective view of an atomizer according to a first embodiment of the design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is a perspective view of an atomizer according to a second embodiment of the design;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is an enlarged top plan view thereof;

FIG. 16 is an enlarged bottom plan view thereof;

FIG. 17 is an enlarged view of area 17 circumscribed in FIG. 2; and,

FIG. 18 is an enlarged view of area 18 circumscribed in FIG. 10.

The dash-dash broken lines in the drawings depict portions of the atomizer that form no part of the claimed design.

The long dash-short dash broken lines in the drawings depict the boundaries of the enlarged views and form no part of the claimed design.

The oblique shade lines in the figures show transparency.

1 Claim, 18 Drawing Sheets
